ELECTRIC HANDSAW

Bert B. Butz, St. Louis, Mo., assignor to Tri-Saw Corporation, St. Louis, Mo., a corporation of Missouri

Application October 23, 1948, Serial No. 149,258

Term of patent 14 years

(Cl. D93—3)

To all whom it may concern:

Be it known that I, Bert B. Butz, a citizen of the United States, residing at St. Louis, State of Missouri, have invented a new, original, and ornamental Design for an Electric Hand Saw, of which the following is a specification, reference being had to the accompanying drawing, forming part thereof.

Figure 1 is a side elevation of an electric hand saw, showing my new design;

Figure 2 is a top plan view thereof;

Figure 3 is a bottom view thereof;

Figure 4 is a front elevation;

Figure 5 is a rear elevation; and

Figure 6 is an elevational view of the side opposite that shown in Figure 1.

The saw blade shown in Figure 1 is omitted in the other figures for convenience of illustration.

The dominant features of my design reside in the portions shown in full lines.

What I claim is:

The ornamental design for an electric hand saw, as shown and described.

BERT B. BUTZ.
